UNITED STATES PATENT OFFICE.

PLINY T. LITCHFIELD, OF SOUTHBRIDGE, MASSACHUSETTS.

LOOM-SHUTTLE.

SPECIFICATION forming part of Letters Patent No. 407,958, dated July 30, 1889.

Application filed April 2, 1889. Serial No. 305,660. (No model.)

To all whom it may concern:

Be it known that I, PLINY T. LITCHFIELD, of Southbridge, county of Worcester, State of Massachusetts, have invented an Improvement in Loom-Shuttles, of which the following description, in connection with the accompanying drawings, is a specification, like letters on the drawings representing like parts.

10 This invention has for its object to provide a loom-shuttle with means for clamping and holding firmly upon its spindle one end of a cop-tube—such as commonly employed upon mule-spindles—thus enabling mule-spun cops 15 to be taken directly from the mule-spindles and be employed economically in loom-shuttles.

In accordance with my invention, the shuttle-spindle, provided with a shoulder to act as 20 a stop for one end of the usual cop-tube, composed of paper, cloth, or metal, has combined with it a finger, which, as the spindle is turned into the shuttle in position for weaving, catches the cop-tube near its end, clamping 25 the latter between the finger and the spindle, firmly holds the cop-tube in position on the spindle until the yarn or thread has been exhausted or unwound therefrom.

The clamping-finger serves to prevent any 30 longitudinal movement of the cop-tube upon the spindle after the spindle has been turned into the shuttle-body.

Figure 1, in longitudinal section, represents a loom-shuttle provided with a cop-tube holder embodying my invention. Fig. 2 shows a modified form of my invention, and Fig. 3 is a section across the spindle and cop-tube near the end of the finger.

The shuttle-body *a*, of any usual shape, has 40 a spindle *b*, of usual shape, it having a shoulder, as *2*, against which is abutted one end of the cop-tube *c*, of usual construction, or such as commonly employed on mule-spindles to receive the yarn being spun in the mule.

45 The spindle shown in Fig. 1 has as its fulcrum a pin *d*, and the spindle is retained upon the said fulcrum-pin by means of the usual spring-actuated pin *e* and spiral spring *e'*. The spindle in Fig. 1 has connected to it

50 by a rivet *3* the cop-tube-holding finger *f*, it being composed of thin metal, preferably spring metal, the free end of which is pref-

erably of concavo-convex shape, as shown at 4, to come against and fit snugly the exterior portion of the cop-tube at or near the shoulder *2* when the spindle is turned into the shuttle-body, as shown in the drawings. When the spindle is lifted or turned outwardly from the shuttle-body, the clamping-finger meets the pin *6*, which arrests its movement and carries the end 4 away from the cop-tube, thus leaving the latter free to be moved longitudinally upon the spindle.

In Fig. 2 the cop-tube-holding finger is somewhat differently shaped from that shown in Fig. 1, it being pivotally connected at *8* to the head of the usual spindle, having its fulcrum on a pin *10*, the head of the spindle being acted upon by a spring *12*, of common construction, the operation of which is well understood. When the shuttle-spindle shown in Fig. 2 is turned into the shuttle, as indicated, the finger *f* meets the shoulder *13*, (shown as forming part of the shuttle-body,) and the shuttle-spindle, acted upon by the spring *12*, is pushed upon in such direction, while the finger *f* rests against the shoulder *13*, that the end of the finger acts against and clamps the cop-tube.

By simply turning the spindle shown in Fig. 2 outwardly the contact of the finger with the shoulder *13* is released, thus releasing the pressure between the finger and the cop-tube.

I do not desire to limit my invention to the exact shape of the end of the finger to come in contact with the cop-tube; but I prefer to shape it so as to present a concavo-convex portion to extend somewhat around the cop-tube.

90 I claim—

The combination, with a shuttle-spindle having a shoulder or stop to support one end of the cop-tube, of a cop-tube-holding finger to clamp the said cop-tube between itself and the shuttle-spindle, substantially as described.

In testimony whereof I have signed my name to this specification in the presence of two subscribing witnesses.

PLINY T. LITCHFIELD.
